The ornamental design for a charging cable apparatus, as shown and described.

DESCRIPTION

FIG. 1 is a perspective view of a charging cable apparatus according to the present invention;

FIG. 2 illustrates a front view thereof;

FIG. 3 illustrates a back view thereof;

FIG. 4 illustrates a right side view thereof;

FIG. 5 illustrates a left side view thereof;

FIG. 6 illustrates a top view thereof;

FIG. 7 illustrates a bottom view thereof;

FIG. 8 illustrates a front prospective view of a charging cable apparatus, with the charging cable shown in an alternate position;

FIG. 9 illustrates the back perspective view thereof; and, FIG. 10 illustrates a bottom view thereof.

The broken lines shown represent unclaimed subject matter and form no part of the claimed design.
